Letters of Patent

The Schedule referred to in these Letters Patent and making
part of the same, containing a description in the words of the
said John R. Campbell and Henry Cyrus Campbell themselves of
their improvement in Door Locks and other fastenings.

To all to whom these Presents shall come,
Be it known, that we, John Read, Campbell & Henry Cyrus
Campbell both of Charlestown in the county of Middlesex and
Commonwealth of Massachusetts, have invented a new and useful
improvement in the Lock for Doors or such like fastenings, and
the following is a full and exact description of the construction
and operation of the said Machine as invented or improved by
us.

The principle upon which we ground our improvement
is, that certain points of the arrangement are to be brought to
coincide before the bolt can be shot or withdrawn, which point
can be so arranged that without some clue to be guided by
it becomes almost hopeless to attempt their reconnection, and
this clue can be given by a combination of certain figures on
the outside. This known principle we improve the construction
of this, see Fig. 1. A represent the enclosing case of the Lock
B the bolt or bolts. C the cross bar running across the case, and
connecting the bolts. D the catch bar to contain the catches
into which the key is to be applied. E the spring behind said
catch bar, bearing against the point F... of the wheels which con-
tain the numerous balks or obstacles. F is intended to perplex &
also I the true points of use. I is the axis of the outside wheels
fitting tightly into I, but capable of being displaced in order to
move round the outside or under wheels containing the numbers

when it may be desired for precaution to change the combination. To the circle of numbers on the outside case, and around the index wheels. Between the wheels h is placed the pivot rod L supported so as to revolve on its axle, and at one end is placed the cross catch M , so adjusted as to pass through the open rings at the true point I by the revolution of the pivot rod L , whenever said points are brought opposite to each other.

This revolution is effected by means of the short rod N continued from the pivot rod L , sufficiently far towards the cross bar C , to touch it so that when it is applied against the side thereof, it acts as a stopper to the bolts being withdrawn when locked. It is operated on or elevated so that the cross bar C may be shoved under it, to unlock by means of a small hook or key through the hole O and to lock it again or rather secure it after it is locked, the same hook is applied to draw it down against the side of the cross bar. Now by changing or turning round the index wheels on the outside so as to derange the numbers, they can scarcely be returned to their right places by any attempts, unless the proper combination of numbers is known. The index wheels P on the outside have to each a row of numbers around the case and also another on the outside of the case, is adapted to them so that any two may be specified to be brought together as the clue.

We also contemplate another mode of construction which may be used separately or in conjunction with the one above described, and we effect it thus. Let A represent the box in Fig. No. 2, having the holes B through it made by drilling two holes near to each other and cutting a communication between them, narrower than the diameter thereof. C are two or more pins extending across the case D and passing through the holes B at which part they are flattened, leaving shoulders and thus enabled to permit the connecting slit between the holes B to slide on this flat part which can of course only be done, when

141

They are presented in that one position, two or more of these parts may be constructed on each pin and at different inclinations so as to operate as obstacles when it is desired to present them, the each one when not desired to be in use, must have a pin through it to prevent its interfering. One end of each pin is furnished with a screw to work in the case so as to draw it further in if required in making the change. The other end is made with a pipe P , or hollow squared for the reception of the key intended to turn the pipe pin, and has two or more rings J , around its circumference numbered. The key has like rings J , and there are also two lines I , passing through these rings likewise numbered, and lastly around the case encircling the pipe pin are rings J , of numbers also. K , is a brace intended to keep the bolt in its place. L , is a pin for the reception of the key to work in the catches M , of the bolt. M , is a pin for the purpose of a pivot to the flat piece O , placed parallel and adjoining the bolt. O , is intended to rest on the round part of the pins C , when they are not in their proper position but as soon as they are, it will fall into the flat part which is made purposely longer on one side to receive it and at which time the bolt may be thrust back over a small stop P , which is fixed in O , to prevent it when the said pins are not rightly placed. It will be seen that by means of the numbers on the pipe, the key and the case, the same changes and obstacles may be presented as in the first described mode.

What we claim as our invention and not previously known or used and for which we now ask Letters Patent is, First, the balks or obstacles on the wheels intended to perplex in attempting to find the true points. Secondly, The Index plates or wheels as applied. Thirdly, The arrangement effected by the first rod, with its cross catch and its short rod continued to the cross bar running across the lock after the manner already shown. These are the parts of the first mode.

We also claim in the second mode the additional flattened parts of the pins intended to present balks or difficulties as

provided for in the first mode, also the construction and application of the flat piece placed parallel with and adjoining the bolt as shown, and lastly the application of the rings and lines of number on the pipe and key as well as on the face of the lock as set forth.

In Testimony, that the above is a full description of the manner of constructing our improvement as invented by us, we have hereunto set our hands this eighteenth day of November - in the year of our Lord One Thousand Eight Hundred and Thirty five
